(57) **CLAIM**

I claim the ornamental design for a light fixture, as shown and described.

DESCRIPTION

FIG. 1 is a perspective view of a light fixture.

FIG. 2 is bottom view of the light fixture shown in FIG. 1; and,

FIG. 3 is a side view of the light fixture shown in FIG. 1. The present application is directed to the shape and contour of the design illustrated in the drawings. The broken line showing of the environment is for illustrative purposes only and forms no part of the claimed design.
